UNITED STATES PATENT OFFICE

MENELAUS MURUFAS, OF LOS ANGELES, CALIFORNIA

ADVERTISING DEVICE

Application filed July 31, 1930. Serial No. 472,034.

This invention relates to advertising devices, and has for an object the provision of a novel advertising device which includes an endless curtain so arranged within a suitable housing, that it is adapted to be continuously moved across a window through which advertising matter carried by the curtain, may be observed. The advertising device of the present invention, is an improvement over 10 that of my copending application, Serial No. 348,486, filed March 20, 1929.

Another object is the provision of an advertising device of the general character described, in which the endless curtain carrying 15 the advertising matter, is interchangeable with others, so that the device may be varied at will to convey to an observer, whatever intelligence may be desired.

A further object is to provide an advertising device of this general character, which is 20 of an exceedingly simple nature, being composed of relatively few and simple parts, and which is of such a nature that the screen carrying the advertising matter, may be removed and replaced by another, with the 25 utmost ease.

This invention possesses other objects and advantageous features, some of which, with those enumerated, will be set forth in the following description of the invention's particular embodiment which is illustrated in the drawings accompanying and forming a part of the specification.

Referring to the drawings: 30 Figure 1 is a front elevation of the advertising device of the present invention.

Fig. 2 is a transverse, vertical, medial sectional view.

Fig. 3 is a longitudinal, vertical sectional view taken upon the line 3—3 of Fig. 2, with the direction of view as indicated.

Fig. 4 is a transverse, vertical sectional view taken upon the line 4—4 of Fig. 3, with the direction of view as indicated.

45 In terms of broad inclusion, the advertising device of the present invention comprises a housing having a window in a wall thereof, and adapted to removably receive a framework upon which a plurality of rollers are journaled. An endless curtain is carried by

the rollers, suitable driving means being associated therewith so as to cause continued motion of the curtain upon the rollers, whereby that portion of the curtain which is visible through the window of the housing, is 55 continuously changed. The curtain is provided with translucent areas arranged in the form of letters or other graphic representations wherby information may be conveyed to an observer; and a light source is provided 60 behind that portion of the curtain which is visible through the window so as to increase the visibility of the translucent areas. An important feature of the invention lies in the fact that the frame may be removed from the 65 interior of the housing, and the curtain removed from the rollers to permit its being replaced by another carrying different advertising matter, thus permitting the use of 70 the machine to advertise different commodities at different times.

Specifically describing that embodiment of the invention which at present appears to be the most practical, my improved advertising device comprises a housing 6 which is 75 preferably more or less ornamental in external appearance, and in the front wall 7 of which a preferably relatively large aperture 8 is provided, forming a window through which a curtain may be observed. The back wall 11 of the housing 6, is removably attached by means of a plurality of screws 12 which extend through the back adjacent its edges, and are threaded into a flange 13 formed by bending inwards the after edges 80 of the top 14 and side walls 16.

Removal of the back 11 permits access to a frame 17 comprising a base 18 resting loosely upon the bottom 19 of the housing 6, and a pair of spaced sides 21 and 22. The side 21 is rigidly secured to the base 18, at or adjacent one end thereof, and rises vertically therefrom. However, the side 22 is not directly connected to the base 18—instead, it is provided with a brace 23 removably attached to the lower end of the side 22 by preferably a plurality of screws 24, and to the base 18 adjacent the other end thereof, by a screw 26. When the brace 23 is removed, the side 22 is adapted to be supported by means of a re- 85 90 95 100

reflector 27 which is rigidly attached at one end to the side 21, and at the other end to the side 22. This reflector is substantially triangular in cross-sectional configuration, and 5 comprises preferably flat upper and lower sides 28 and 29 respectively, having their end edges turned outwards to form flanges 31 and 32 respectively, whereby they may be rigidly attached to the upright sides 21 and 22 of the 10 frame 17. These sides 28 and 29 of the reflector, are arranged in angular relationship with each other, diverging toward their forward edges; and their inner faces are highly polished or are coated with some highly reflective material so as to increase the efficiency of preferably a plurality of electric-light bulbs 33 mounted in sockets 34 which are carried by the reflector 27 adjacent the convergent after edges of the sides 28 and 29 15 thereof. The reflector 27 is arranged so that it registers with the window 8 in the front wall 7 of the housing 6.

A plurality, preferably four rollers 36, 37, 25 38, and 39, are journaled in and extend between the sides 21 and 22 of the frame 17. Two of these rollers, say the rollers 37 and 38, are arranged in vertical alignment adjacent the front of the frame 17, and the other rollers 36 and 39 adjacent the after edge of the 30 frame. The rollers 36, 37, and 38 are carried in rigid journals 41, 42, and 43, which are formed preferably in ears extending from the corners of the sides 21 and 22. However, the journals 44 for the two ends of the roller 39, are adjustable, being formed in plates 46 35 adjustably secured adjacent the upper after corners of the sides 21 and 22, by means of screws 47 or their equivalent.

An endless curtain or film 51 is carried by 40 the rollers 36, 37, 38, and 39. This curtain is composed preferably of suitable translucent or transparent material such as tracing cloth, celluloid or the like, and is adapted to receive a coating 52 of opaque material having translucent or transparent areas 53 left therein, these areas 53 being so arranged that they define letters or other graphic representations. Whereas Fig. 1 shows a device 45 with a curtain 51, the major portion of which is opaque, having transparent areas 53 defining letters, it should be understood that the major portion of the curtain may be left translucent or transparent, as the case may be, with the opaque coating applied only in 50 the form of the letters, so that the letters stand out as opaque areas against the transparent or translucent background.

Means are provided for moving the curtain 51, the forward run 54 of which, extends 60 across the window 8 in close proximity to the front wall 7 of the housing 6 when the device is in assembled relationship. Preferably, I employ for this purpose, a small electric motor 56 mounted upon the base 18 of the frame, and connected to the roller 36 by means of a

70 pulley 57 on the roller, and a drive pulley 58 carried by the shaft of the motor 56, a suitable belt 59 engaging both pulleys so that energization of the motor 56 results in rotation of the roller 36.

Whereas any suitable advertising matter 75 may be arranged upon the curtain 51, the device is herein shown and described as having a restaurant menu inscribed upon the curtain.

With the curtain constructed in this manner, the device is of utility as an advertising medium to be placed in the window of a restaurant so as to advertise the daily menu of that 80 restaurant. It could also be positioned inside the restaurant in full view of the patrons, so that they may be referred to the foods listed thereon, and the price of each, thus avoiding the necessity of providing each patron or each 85 table with an individual menu.

At the termination of a day's business, or at any other time when the menu is to be changed, the certain 51 may easily be removed and a new one 90 substituted therefor.

This is accomplished by removing the back 11 of the housing 6, drawing the frame 17 therefrom and removing the brace 23. Then the curtain 51 may 95 easily be slipped over those ends of the rollers 36 to 39 inclusive, which are associated with the frame side 22.

This may easily be accomplished by slackening the screws 47 to permit the journal plates 46 to move inwards so as to decrease the tension on the curtain 51.

A new curtain which has previously been prepared with the appropriate advertising matter, or the new menu, may then be slipped onto the rollers, the roller 39 shifting outwards to impose suitable tension upon the curtain, and clamped in position by tightening the screws 47.

The frame 17 should then be slipped back into the housing 6 and the back 11 fastened in position by means of the screws 12. The housing should then be placed in a conspicuous position, the lamps 33 illuminated and the motor 56 energized, thus causing the curtain 51 to move continuously past the window 8 with light from the lamps 33 100 shining through the translucent or transparent areas of the curtain, thus materially increasing the visibility of the characters formed thereon.

105 It is to be understood that the details of the invention as herein disclosed, are subject to alteration within the spirit or scope of the appended claims.

110 I claim:

115 1. In an advertising device, a frame comprising a base and a pair of side walls, one of 120 said walls being rigid with said base and the other being disconnectably mounted thereupon, a reflector carried by one of said walls, a light-source in said reflector, a plurality of 125 rollers journaled on and extending between said side walls, two of said rollers lying in a plane substantially parallel to and adjacent the front of said reflector, an endless curtain 130

carried by said rollers and having translucent areas therein arranged to present advertising matter, and means for rotating one of said rollers.

5 2. An advertising device comprising a housing having a window in a wall thereof, a frame removably receivable within said housing and comprising a base and a side rising rigidly from an end thereof, a reflector rigid with said side and extending therefrom toward the other end of the base, a second side rigid with said reflector, a brace carried by said base and removably attached to said second side, rollers journaled in and extending 10 between said sides, two of said rollers being in alignment adjacent the front of said housing, an endless curtain carried by said rollers and having translucent areas therein arranged to present advertising matter, a light source in 15 said reflector, and means for rotating one of said rollers.

20

3. An advertising device comprising a housing having a window in a wall thereof, a frame removably receivable within said 25 housing and comprising a base and a side rising rigidly from an end thereof, a reflector rigid with said side and extending therefrom toward the other end of the base, a second side rigid with said reflector, a brace carried by 30 said base and removably attached to said second side, rollers journaled in and extending between said sides, two of said rollers being in alignment adjacent the front of said housing, an endless curtain carried by said rollers 35 and having translucent areas therein arranged to present advertising matter, another of said rollers being adjustable to vary the tension of said curtain, a light source in said reflector, and means for rotating one of 40 said rollers.

In testimony whereof I have signed my name to this specification.

M. MURUFAS.
